UNITED STATES PATENT OFFICE.

SYLVANUS F. BOWSER AND AUGUSTUS BOWSER, OF FORT WAYNE, INDIANA.

MEASURING-PUMP.

SPECIFICATION forming part of Letters Patent No. 480,550, dated August 9, 1892.

Application filed May 2, 1892. Serial No. 431,416. (No model.)

To all whom it may concern:

Be it known that we, SYLVANUS F. BOWSER and AUGUSTUS BOWSER, citizens of the United States, residing at Fort Wayne, in the county 5 of Allen and State of Indiana, have invented certain new and useful Improvements in Measuring-Pumps, (Case B;) and we do hereby declare the following to be a full, clear, and exact description of the invention, such as will enable others skilled in the art to which it appertains to make and use the same.

This invention relates to measuring-instruments, and more especially to that class thereof known as "measuring-pumps;" and the object of the same is to effect certain improvements in the gaging mechanism for controlling the amount of liquid which the pump shall discharge. This object is attained by the mechanism hereinafter more fully described 20 and claimed, and as illustrated in the accompanying drawings, wherein—

Figure 1 is a side elevation of the storage-tank, partly in section, to show the contained mechanism in elevation. Fig. 2 is a vertical 25 section of said mechanism. Fig. 3 is a plan view of a portion of the top of the tank. Fig. 4 is a reduced vertical section of a modified form of said mechanism, using a slide on the top of the tank. Fig. 5 is an enlarged plan 30 view of said slide.

In United States Letters Patent No. 372,250, granted to us on October 25, 1887, we employed an oscillatory stop-rod in connection with a plurality of stops thereon and a single collar 35 on the pump-rod. Prior to that patent devices had been patented employing oscillatory pump-rods having radial stops engaging beneath the tank-cover, and also others employing notched pump-rods and slides on the cover 40 whose tips engaged said notches. The present invention is an improvement over all these devices in that it employs an auxiliary rod for the stop-collars, and the collars (and slide when it is used) differ from those hitherto constructed with apparent resultant advantages.

Referring now to the accompanying drawings, the letter A designates a tank, below whose bottom *a* the pump-cylinder B is preferably located in order that all the liquid 50 within the tank may be drained by this device. Said cylinder is situated within a can C, which communicates with the interior of

the tank A at *c*, and the liquid in the can finds a passage through an upwardly-opening valve V into the pump-cylinder below its solid 55 head *b*.

The action of the pump as illustrated, though not material in its construction to the present case, is that when the pump-rod D is forced down the liquid is expelled or forced 60 upward through and out of the delivery-spout J, which leads from within the can, as shown, and passes through the top E of the tank A, as does the rod D, whereby it may be operated from the exterior of the tank, all as will be 65 clear.

Coming now to the present invention, the letter F designates a supplemental or gage rod cranked near its ends, so that its body will stand at some distance from yet parallel with 70 the pump-rod D, said ends embracing said rod and being confined between collars *d*, which may be provided with set-screws *d'* or other means for rendering them adjustable at times. Thus it will be seen that the gage-rod may 75 swing to a certain extent around the pump-rod if the latter be cylindrical, or with it if it be angular, and to permit such swinging the top E of the tank is provided with a hole W for the pump-rod and with a curved slot 80 I struck around the hole W for the gage-rod, and having an extension *i* at one extremity, preferably radial to the pump-rod, as seen in Fig. 3. To the gage-rod are secured two collars or stops G and H in any manner, as be- 85 tween nuts N, as seen in Fig. 1, by set-screws N', as in Fig. 2, or otherwise, the uppermost one G being radial to the pump-rod and the lowermost one H standing at some angle to the radial line from the pump-rod through 90 the gage-rod. The stop G is of such size that when the gage-rod stands at the proper extremity of the slot I this stop may move upward through the extension *i*, and the lowermost stop H will strike beneath the top E; 95 but when the gage-rod stands at the opposite extremity of the slot I the uppermost stop G will strike beneath the top E as the rod D is lifted.

The two stops being properly set axially to and adjusted longitudinally on the 100 gage-rod and the latter adjusted properly on the pump-rod, it will be clear that the operator may control the degree of rise of the pump-head within its cylinder, and hence of

the amount of liquid which is permitted to pass thereinto and be ejected from the spout J. Thus if the upper stop G strikes the top E the pump will admit and eject one charge, 5 (say one quart); but if allowed to pass through the extension i, so that the lower stop H strikes the top E, the pump will admit three charges, (say three quarts.) To deliver two charges, the pump is operated twice at the 10 stop G; three, once at stop H; four, once at each, and so on; or any other arrangement of these stops could be made, perhaps so that they would deliver in fractions of charges—one in pints and the other in quarts, for instance. If the gage-rod turns upon the pump-rod, it will be set by hand by the operator. If 15 it is fast thereon, he simply turns the handle of the pump-rod before raising it, all as will be clear.

20 In Figs. 4 and 5 we have shown a slight modification of the construction described above. In this case the pump-rod is preferably square or angular, though it may here also be round, so as to turn, and the cover or 25 top E provided with the same curved slot. However, we prefer that the pump-rod D' pass through a square hole in the top E' and the gage-rod F'' pass through a hole I', which is of sufficient size to permit the passage of 30 the stop G', and the stops are so arranged as to project in different radial lines from the gage-rod as above. A slide J' is in this case provided, preferably having a slotted body j, which moves under a headed screw j', although any means may be provided for 35 controlling the slide. The tip of the latter is adapted to move over and partially close the hole I', as shown in Fig. 4. In this instance the stop G' will strike the slide and one 40 charge only can be ejected. When the slide is retracted, this stop may pass through the hole I', but the stop H' will strike beneath the top E', and three charges will be ejected, the 45 operation being substantially the same as above explained, except that the user adjusts the slide instead of the gage-rod. It will be clear this slide may be used in connection with the curved slot I of Fig. 3 by locating the slide so that it will cover the extension i.

50 Indeed it may in some cases be desirable to provide the device with both forms of gaging mechanism in order that the slide may be thrown into use if the gage-rod should ever stick or become bent so that it will not readily turn within and from end to end of the 55 curved slot I. In this event the extension i simply takes the place of the hole I' of Fig. 4, and the device is operative in this way until the tank is empty and can be cleaned again.

60 The parts are of any desired size, material, and shape, so long as no departure from the spirit of this invention is adopted.

The uses and operation of the whole are well known to those familiar with this class 65 of machines, and we will not therefore explain it in further detail.

What is claimed as new is—

1. In a measuring-pump, the combination, with a tank, a pump therein whose rod passes through the tank, and a delivery-spout, of a 70 gage-rod also passing through the tank, its body standing parallel with the pump-rod and its ends being cranked and connected with said pump-rod, and adjustable collars on the pump-rod against the ends of the gage-rod, 75 substantially as and for the purpose set forth.

2. In a measuring-pump, the combination, with a tank, a pump therein whose rod passes through the top of the tank, and a delivery 80 spout, of a gage-rod whose body stands parallel with the pump-rod and passes through a hole in said top and whose ends are connected with said pump-rod, and stops on said gage-rod respectively adapted to pass through the gage-rod hole and to strike under said 85 top, as and for the purpose set forth.

3. In a measuring-pump, the combination, with a tank, a pump communicating therewith and whose rod passes through the top of the tank, and a delivery-spout, of a gage- 90 rod secured to said pump-rod parallel therewith, an upper stop on said gage-rod, the top of the tank having a hole through which this rod and stop may move, substantially as described, for preventing the passage of 95 this stop therethrough, and a lower stop arranged so as not to pass through said hole, as and for the purpose set forth.

4. In a measuring-pump, the combination, with a tank having in its top a hole and adjacent thereto a curved slot struck around 100 said hole and having a radial extension at one extremity, a pump communicating with said tank and whose rod passes through said hole, and a delivery-spout, of a gage-rod secured 105 to said pump-rod and moving longitudinally through said slot and two stops on said gage-rod, the uppermost being radial to the pump-rod and adapted to pass through the extension, as and for the purpose set forth. 110

5. In a measuring-pump, the combination, with a tank having in its top a hole and adjacent thereto a curved slot struck around 115 said hole and having a radial extension at one extremity, a pump communicating with said tank and whose rod is square and passes loosely through said hole, and a delivery-spout, of a gage-rod having cranked ends secured to the pump-rod so as not to turn thereon, its body being parallel with said pump-rod and moving through said slot, and two 120 stops on the gage-rod, the uppermost being adapted and the lowermost not adapted to pass through said extension, as and for the purpose set forth. 125

6. In a measuring-pump, the combination, with the tank having in its top two holes, a slide mounted on said top and adapted to partially close one hole, a pump communicating with the tank and having a delivery-spout, and a pump-rod passing through the unimpeded hole, of a gage-rod connected with the pump-rod and passing through the remaining hole, and two stops thereon, the up- 130

permost one being adapted to pass through the gage-rod hole when the slide is retracted, but the lowermost one not being adapted to pass through said hole, as and for the purpose set forth.

- 5 7. In a measuring-pump, the combination, with a tank having in its top a hole and adjacent thereto a curved slot struck around the hole and having an extension at one extremity, a pump communicating with the tank and whose rod passes loosely through said hole, and a delivery-spout, of a gage-rod secured at its ends to the pump-rod, so as to turn

therewith, its body moving in said slot, two stops on said gage-rod, and means, substantially as described, for preventing the uppermost stop from passing through said extension, as and for the purpose hereinbefore set forth.

10 In testimony whereof we affix our signatures in presence of two witnesses.
